UNITED STATES PATENT OFFICE.

WALTER W. PHILLIPS, OF FRANKFORD, DELAWARE.

FIRE ESCAPE.

Application filed February 21, 1928. Serial No. 255,876.

This invention relates to flexible ladders and has particular reference to such apparatus designed particularly for use as fire escapes, and the invention is in the nature of an improvement over the fire escape shown and described in Letters Patent of the United States No. 1,647,841 issued to me on the 1st day of November, 1927.

Among the objects of the invention is to improve this class of devices in such particulars among which are the following: First, better facilities for the folding or nesting of the flexible ladder when in idle or inactive position usually within easy reach of a window within a building and preferably when stored in an article of furniture such as a settee, window box, or other receptacle; secondly, to so construct the head or upper portion of the ladder as to render it impossible of failure for co-operation properly with a building unit such as a window sill. While the mechanism already patented to me is satisfactory in the main when properly adjusted, it has been found to be unsatisfactory with respect to the details of refinement herein referred to.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a diagrammatic indication of how the improved fire escape or flexible ladder may be nested or folded in compact condition for ordinary inactive use in an article of furniture which may be located at any convenient place within a building as adjacent to a window.

Fig. 2 is a similar view showing the extended position of the ladder for use as a fire escape and with easy access thereto through the window and over said article of furniture as a step.

Fig. 3 is an outside elevation of the ladder as would be seen looking toward the left in Fig. 2.

Fig. 4 is a side elevation of a modification.

Fig. 5 is a front elevation of the principal parts shown in Fig. 4.

Referring now more specifically to the drawings, I show at 10 a fragment of a building wall in which is built a window 11 having any suitable sill structure 12, and at any convenient point within the building as upon a floor 13 is an article of furniture or receptacle 14 in the nature of a settee, box chair, or window box, the same being shown herein as comprising a seat 15 hinged at 16 to swing upward and rearward against the back 17 and between a pair of arms 18 at least one of which is hinged at 19 to swing upward and rearward as shown in Fig. 2 so as to make free clearance between the region of the seat 15 and the window sill when the fire escape is to be used as such. It will be noted that the article of furniture is portable, not being attached to any other part of the building and so may be moved about to any part of the building or room or in front of any desired window for use.

The ladder portion proper comprises a series of rungs 19 of any suitable construction, each mounted between and supported by a pair of side links 20, all the side links 20 being in two parallel planes. Auxiliary links 21 likewise arranged in pairs are connected to the main links 20, the same being articulated or jointed at 22 to the main links close above the axes of the rungs. Washers or other spacers 23 may be employed between the main and auxiliary links to insure ample clearance and freedom of movement of the links with respect to one another. The auxiliary links are all arranged in two parallel planes, the plane of each series of auxiliary links being within the plane of the adjacent series of main links or so disposed toward the center of the ladder structure as to compel the rungs 19 to impinge against the outer edges of the auxiliary links when the ladder is in use. This compels the flexible ladder to assume the position in side view as shown in Fig. 2 and thus insuring that the rungs 19 shall be held sufficiently spaced outward from the outside wall of the building so that by no possibility will the persons' hands or feet be interfered with in passing downward over the ladder in escaping from the building as during a fire. That is to say, the construction of the ladder is such that the pairs of main and auxiliary links shall assume an angular position with respect to each other and compel the axes of the pivots 22 to stand outward to a substantial distance.

Fig. 4 is a side elevation of a modification. Fig. 5 is a front elevation of the principal parts shown in Fig. 4.

say at least four or five inches from the building wall and for the rungs to be thereby held outward from the building still farther. Obviously the number of rungs and pairs of links connecting them may be as many as desired according to the height of the window to be protected by the use of the fire escape and it will be understood that the flexible ladder when ejected outward and downward from the window will reach substantially to the ground or other point of escape.

The uppermost main links 20 are jointed at 24 to the outer or lower ends of a pair of master links 25 to which are connected preferably pivotally at 26 a plurality of hooks 27 of sufficient size and strength to engage inward and downward over the window sill 12 and hold positively the entire ladder structure when in extended position. A rung 20 19^a extends between the master links 25, and for the convenience of the person making the escape another rung 19^b may be located between the inner portions of the hooks 27.

The mode of operation may be briefly explained as follows, it being borne in mind that in the case of emergency such as a fire when people are always more or less excited if not frantic, the directions of the use of the appliance must be not only simple and easily understood, but the construction must be such that the mechanism can not fail to operate or be brought into proper position of adjustment. The article of furniture being placed adjacent to the window preferably with the arm 18 close to the window, such arm 18 is swung upward to the position of Fig. 2, the seat 15 is swung upward in the same general direction, the outer or loose end of the flexible ladder is lifted from the receptacle 40 and started outward and downward through the window, the weight of which continues the extension of the ladder until the hooks 27 reach the window sill and engage thereover. The construction is such that the hooks can not fail to engage and hold upon the window sill. However, to make it absolutely impossible for the ladder to pass too far out through the window, flexible connections such as chains 28 are employed to anchor the same loosely to the inside of the receptacle as shown at 29. It is to be understood, however, that the connections 28 are not intended to sustain the weight of the ladder and persons passing downward over it. After the latter is adjusted as just explained the seat 15 is returned to normal closed position, notches 30 being formed in the seat to accommodate the chains 28 and so the seat 15 becomes a step to enable any persons within the room, such as women, children, or aged people to pass easily over the seat and climb out through the window

and thence down over the ladder rungs to escape.

With respect to the modification shown in Figs. 4 and 5, the building construction and article of furniture arrangement will be understood as the same as already described together with the construction and action of the hooks 27 and parts associated therewith. In place of the main links 20, however, I employ short curved links 31 between each pair of which is extended transversely a rung 19. The links 31 are bowed outward from the building so as to insure proper offset of the links from the building for the purposes above set forth. Pairs of longer links 32 are sandwiched between the main short links 31, the links of each series having the same plane as described in connection with the first arrangement. By making the links 32, however, substantially longer than the curved links, the nesting or folding of the flexible ladder is rendered much more facile and convenient than would be true if the links 31 were longer than those at 32.

I claim:

1. A flexible ladder comprising a series of main links, auxiliary links interconnecting the main links, the main and auxiliary links extending in two parallel planes lengthwise of the ladder, and rungs extending transversely of said planes and connecting the corresponding main links, said rungs engaging the main links at the lower ends thereof, each auxiliary link engaging a main link between the ends thereof and in proximity to the rung, and each auxiliary link engaging at its lower end an upper end of a main link beneath the auxiliary link, the rungs co-acting with the adjacent auxiliary links to retain the latter and the main links at a predetermined angle with respect to each other and the rungs in spaced relation to a wall.

2. A flexible ladder comprising a series of main links extending in parallel planes lengthwise of the ladder, a series of rungs extending transversely of the ladder and connected to the main links at their lower ends, each main link having two pivotal points one of which is at an upper end of the auxiliary link, and the other at a point intermediate the upper end and the rung and in proximity to the latter, and a series of auxiliary links successively interconnecting the main links at the pivotal points thereof, the rungs bearing against the auxiliary links to retain the main links at an angle with the auxiliary links and the rungs in outward spaced relation to the wall of a building.

In testimony whereof I affix my signature.

WALTER W. PHILLIPS.
